UNITED STATES PATENT OFFICE

2,189,408

MECHANICALLY OPERATED TOOTH BRUSH

Theodore Seifried, Nashville, Tenn.

Application May 19, 1937, Serial No. 143,579

1 Claim. (Cl. 15—28)

One of the most important features of my invention resides in the curved tapered form of the body of my device with the operating mechanism mounted in the cap whereby the spring is easily wound and controlled and the brush is disposed in the proper position to permit the user to clean with ease and facility both the inner and outer surface of the teeth.

My invention relates to improvements in mechanically operated tooth brushes, that is to say, a tooth brush operated by a spring motor embodied in the brush structure as a whole.

One object of my invention is the provision of a tooth brush of the character stated which will operate after the manner of a dentist's instrument and which will reach every crevice of the teeth from the inside and outside surfaces of the teeth to insure a most perfect cleaning.

Another object of my invention is the provision of a mechanical or motor operated tooth brush which will be of the most convenient and desirable shape for use in order to permit its perfect handling or manipulation by any person.

Another object of my invention is the provision of a tooth brush of the character stated which will effect a perfect and thorough cleaning of the teeth and which will permit the use of brushes of different sizes and shape, as may be found most desirable.

Another object of my invention is the provision of a mechanically operated tooth brush which all things considered, will possess merit in point of simplicity and durability of construction, which can be made and sold at the right price, and which in every particular will prove highly efficient and practical.

With these objects in view, my invention consists of a motor or mechanically operated tooth brush embodying novel features of construction and combination of parts substantially as described and claimed and as shown in the accompanying drawing, in which:

Figure 1 represents a vertical longitudinal sectional view of a mechanically operated tooth brush constructed in accordance with and embodying my invention.

Figure 2 represents a sectional view taken on line 2—2 of Figure 1.

Figure 3 represents a sectional view taken on line 3—3 of Figure 1, and

Figure 4 represents a sectional view taken on line 4—4 of Figure 1.

Referring by numeral to the drawing, in which the same numbers of reference denote like parts in all the views:

The numeral 1 designates the body portion or handle of my tooth brush which is of hollow curved or flaring construction having a passage 1' in its outer reduced end and formed with screw threads 1'' at its inner open end to receive the threads 2 on the cap 2', which is formed with an opening 2'' for a purpose which will presently appear.

Disposed within and rigidly secured to the handle or body portion contiguous to said cap 2', is the drum or casing 3 in which is mounted the coil spring 3' having one end secured at 3x, to the drum and its other end 3a secured to the shaft 8 which extends outward through the opening 2'', of the cap 2' and is formed with a knurled end 3', for rotating said shaft. Mounted on said shaft 8 intermediate its length is the ratchet wheel 12 which is rotated by the unwinding of the coil spring 3' and which ratchet is retained in place by the lever-operated pawl or dog 13 fulcrumed to the lug 14 and having an arm 15 adapted to receive pressure from the finger to release said pawl 13 from engagement with the ratchet to permit rotation of said ratchet and the shaft 8 under the impulse of said spring 3', and said pawl is held in proper engagement with the ratchet by means of the small coil spring 16 as most clearly shown in Figure 2.

It will be noted that the shaft 8, extends out through the cap 2', and forms a winding stud 30 or stem for placing the spring 3' under tension and permitting the spring to be wound with ease and facility.

From this construction it will be apparent that the outer end of shaft 8 projects beyond the cap 35 and that the turning of the shaft winds the coil spring and carries with it the ratchet wheel, which ratchet wheel when released through the action of the finger-operated pawl or detent imparts a rapid rotation to the shaft 8, and on said shaft 8 at its inner end is mounted the large gear wheel 4, which meshes with and drives the smaller gear wheel 5, mounted on a short stud 5', and to the said gear 5 is connected the flexible shaft 17 which extends through the body portion or handle of the implement and passes through the opening 1', in the reduced end of said handle, and said shaft is formed with a round portion 18 which fits in the socket 19 of the brush head 20 carrying the brush 11.

From the foregoing description taken in connection with the drawing, the operation of my tooth brush will be readily understood and its many advantages be appreciated, and it will be apparent that the spring is wound up by rotation 50 55

of the shaft 8 until the spring has been placed under the desired tension, in which condition it is retained by the ratchet wheel and the manually controlled pawl or detent and that upon the 5 release of such pawl, the ratchet wheel is permitted the necessary revolution to impart rotation through the gear wheel and the flexible shaft to the tooth brush.

It will be apparent that the tool or brush is 10 of the desired size and shape to permit the cleaning of the teeth on their inner and outer faces in a thorough and perfect manner, such as a dentist would perform this operation to effect the thorough removal of any surface accumulation both from the inner and outer faces of the 15 teeth.

It will be evident that a tooth brush constructed according to my invention will operate with ease and facility and that it possesses merit 20 over the tooth brushes in general use from every point of view and that its features of merit will command it as highly desirable, practical and useful.

I claim:

25 The mechanically operated tooth brush herein shown and described, comprising a hollow generally tapering body portion circular in vertical cross section and having its upper wall continuously curving downwardly and forwardly and 30 having its lower wall horizontal at its rear portion and slightly curving downwardly and forwardly at its front portion whereby a conical curved handle is formed, said body portion being

provided at its reduced end with an opening having its axis approximately parallel to the upper wall of said handle, a drum mounted on a horizontal axis in the enlarged open end of said handle and having its rear end open and 5 its front end closed by a wall, a centrally disposed opening being formed in said drum wall, a cap fitting upon the open end of said handle and having an opening axially aligned with the said opening in the wall of the drum, a shaft 10 journaled in the openings of the wall and cap and having its inner end extended beyond said wall and its outer end projecting rearwardly of said cap to form a winding stem, a flat coiled spring arranged in the drum with one end secured 15 to the drum and its other end secured to said shaft to impart rotation to said shaft, a large vertically disposed driving gear wheel secured to the inner projecting end of said shaft, a stud projecting forwardly from the upper portion of 20 said wall of the drum, a small gear wheel on said stud meshing with the said large driving gear-wheel, a flexible shaft having its inner end secured to said stud and curved throughout to conform to the upper curved wall of the handle 25 and with its free end projecting through said opening in the reduced end of the handle, a rotary flat faced tooth brush fitted axially in the end of said flexible shaft, and a manually releasable ratchet mechanism for either holding or 30 releasing the flat spring and thereby controlling its unwinding.

THEODORE SEIFFRIED.
